(57) **CLAIM**

The ornamental design for an equipment support pad as shown and described.

DESCRIPTION

FIG. 1 is a top perspective view of the claimed design; FIG. 2 is a top plan view of the claimed design; FIG. 3 is a bottom plan view of the claimed design; FIG. 4 is a right side plan view of the claimed design; FIG. 5 is a left side plan view of the claimed design; FIG. 6 is a front plan view of the claimed design; and, FIG. 7 is a rear plan view of the claimed design.

The ornamental design which is claimed is shown in solid lines in the drawings. In the drawings, the broken lines depict portions of the equipment support pad that form no part of the claimed design.

The drawings are shown with a symbolic break in length, the appearance of any portion of the article between the break lines forms no part of the claimed design.

1 Claim, 5 Drawing Sheets
